TWO-STROKE INTERNAL-COMBUSTION ENGINE.

1,336,232.

Specification of Letters Patent.

Patented Apr. 6, 1920.

Application filed June 25, 1919. Serial No. 306,721.

To all whom it may concern:

Be it known that I, ALBERT ISLIKER, citizen of Switzerland, residing at Geneva, Canton of Geneva, in the Confederation of Switzerland, have invented certain new and useful Improvements in Two-Stroke Internal-Combustion Engines, of which the following is a specification.

The present invention relates to two stroke internal combustion engines comprising like other known machines of this kind at least one pair of motor cylinders on opposite sides to each other of the crank-pit, at least one pump for the purpose of sending the combustible mixture into the cylinders before the compression of the same and at least one air pump for scavenging out the cylinders, the whole arranged in such a way that during the scavenging 15 and the filling of the cylinders with combustible a certain quantity of pure air will be sent into the same and afterward a gaseous mixture of air and combustible mixture.

20 The distinguishing feature of this engine however is, that the two pumps are formed by the pit of the crank shaft, this chamber being divided by a partition wall set vertically to the shaft into two separate chambers and that said pumps are adapted without the aid of any special distributing means to cause the filling of the cylinders firstly with pure air and then with gaseous material of air and combustible mixture.

25 The suction inlet of the pump of combustible mixture may be provided with a contracted passage way which is intended to prevent the pump during the suction stage of filling entirely with combustible mixture 40 and so as to cause the same to suck in also some pure air through a communicating port between the canals leading to the motor-cylinders which canals form the inlets for the combustible mixture and the air 45 for scavenging the cylinders.

The pump for pure air may be of greater volume than that of the combustible mixture or may present a smaller dead space than the dead space of the pump for the 50 combustible mixture. The distributing ports serving for admitting combustible mixture into the cylinders may have a smaller length parallel with the movement of the pistons, than the ports for admitting the pure air

and may be freed later on during the motor stroke of said pistons. The pure air may be sent to the suction inlet of the air pump from a device furnishing compressed air.

The canals leading from the two pumps to one of the motor cylinders and letting pass the combustible mixture and the air for scavenging purposes may be shut off by a checking device in order to give the facility of putting the corresponding motor cylinder out of service. The motor may also be provided with a device for regulating the sucked-in quantity of combustible mixture and of pure air of the pumps.

The annexed drawing represents one working example of the motor and a modified detail of the same.

Figure 1 is a vertical length section of this working form.

Fig. 2 a cross-section of one of the cylinders.

Figs. 3 and 4 are horizontal sections on lines A—A, B—B of Fig. 1, the connecting rods being omitted.

Fig. 5 is a partial vertical section of the modified detail.

In the form of the invention shown in Figs. 1 to 4 there are two motor-cylinders 1, 2, whereof the parallel axes are in the same horizontal plane, but do not coincide and the open ends of which face each other. These cylinders are rigidly connected with the crank-pit 3 of the engine. This crank-pit carries the bearings of a crank shaft 4 with the two cranks set at 180° with regard to each other and each connected by a rod 5 or 5¹ with the pistons 6 or 6¹ moving within cylinders 1, 2. In the walls of these cylinders the inlet-ports 10^a and 11^a are provided for the combustible mixture and the outlet-ports 12^a, 12^b for the gases of combustion. All these ports are controlled by pistons provided with deflectors for deflecting the incoming gases, spark plugs 16^a, 16^b effect the firing of the combustible mixture.

One of the chambers 21 of the crank pit 3 acts as a pump for the combustible mixture and it communicates to this end with the chamber 19 to the right of the cylinder 1 by means of an opening 20 made laterally in a wall of the crank-pit 3 and through which the connecting rod 5 passes. The chamber 19 may be put in communication with a

neck 13^a by means of the ports 7^a controlled by the piston 6, said neck leading to the carbureter.

Canals 8^b, 9^b leading from the chamber 21 respectively to ports 10^b, 11^b are provided in the walls of cylinders 1, 2 and serve for the introduction of the combustible mixture into the cylinders before the compression and under the control of the pistons 6, 6¹. The dead space of this pump is considerable as it is constituted by the interior volume of the hollow piston 6 and by the chamber 21. On the other part a diffuser of the carbureter, producing a rich combustible mixture presents a passage way small enough that the pump may not be filled entirely with combustible mixture at the suction stroke of this pump.

The pump furnishing the needed air for the scavenging is formed by the chamber 24 of the crank-pit 3, said chamber communicating with the left side chamber 22 of the cylinder 2 by means of an opening 23 made laterally in the wall of the crank-pit 3 and forming the passage-way for the connecting-rod 5¹. In the wall of cylinder 2 there are also port-holes 7^b controlled by the piston 6¹ and connected to a neck 13^b communicating with the atmosphere and provided if needed with a screen. The chamber 24 communicates with canals 8^a, 9^a leading to the ports 10^a, 11^a cut within the walls of cylinders 1, 2 serving for the introduction of air for scavenging purposes into said cylinders and controlled by the pistons 6, 6¹. In order to make the dead space of the pump for air perceptibly smaller than that of the pump for the mixture, the piston 6¹ is provided with an interior partition wall 27 and the crank pit 3 is fitted on the outside with a jointed body 28 projecting into chamber 22, see Fig. 4. On the other side the passage-way of the diffuser of the carbureter has a smaller cross-section than that of the air-inlet into the neck 13^b. The ports 10^a and 10^b on one part and the ports 11^a, and 11^b on the other part, are in the same vertical plane with the axes of the cylinders and have the same axial length, so that they are covered and uncovered simultaneously by the pistons; the exhaust ports 12^a, 12^b however are uncovered by the pistons somewhat earlier than the said ports.

The canals 8^a and 8^b, 9^a and 9^b communicate with each other quite close up to these ports owing to passageways 25, 26 provided within the partition walls separating the same.

The two chambers 21, 24 of the crank-pit are separated by a disk-shaped plate 18 made in one piece with the crank-shaft 4 and provided at its rim with an annular groove jointing with an annular flange of the crank-pit 3. Thus a relatively tight

joint is obtained here, which tightness is not absolutely necessary.

Within the necks 13^a and 13^b checking devices have been provided for, such as butterfly-valves for instance, which are operated from a common shaft 14 carrying a handle 15. A contrivance not represented in the drawing makes it possible to vary by means of this shaft the composition of the gases admitted to the motor-cylinders. Besides a checking-member 17 is arranged within the canals 9^a, 9^b by means of which member the cylinder 2 may be cut out of service.

The operation of this form of the invention is as follows: Supposing the pistons 6, 6¹ are both at their interior end position and are about to move outwardly, they will both compress within the combustion chambers of their cylinders the combustible mixture which has previously been admitted there and will at the same time create a certain vacuum within the chambers 21, 24 and finally will uncover the port-holes 7^a, 7^b. Through the first of these ports a rich combustible mixture coming from the carbureter will enter the chamber 21. The quantity of mixture thus sucked in, owing to the small passage-way of the diffuser of the carbureter, will not be sufficient to fill the chambers 21 and 24. Therefore a supply of fresh air will also be admitted this air coming in through the neck 13^b, the ports 7^b, the chambers 22, 24, then on one side through canal 8^a, passage-way 25, and canal 8^b, and on the other side through the canal 9^a, passage-way 26 and canal 9^b. The four canals 8^a, 8^b, 9^a, 9^b therefore contain only fresh air.

The combustible mixture compressed during the preceding stroke within the combustion chambers will then be fired by the spark plugs 16^a, 16^b, and will explode and expand moving the pistons 6, 6¹ toward the inside until the gases of combustion can escape through the ports 12^a, 12^b. These pistons will compress at the same time the combustible mixture within chambers 19, 21, and the pure air shut up within the chambers 22, 24. As the dead space for the pump of combustible mixture is much greater than the space within the air pump the compression given by the first is not so considerable as that given by the second, to such a degree that a new quantity of fresh air will be pressed at this moment into the chamber 21 through 8^a, 25, 8^b and 9^a, 26, 9^b. These canals and these passages will therefore continue to contain fresh air and the portions of chamber 21 adjoining the canals 8^a and 9^a will also contain pure air. The pistons 6, 6¹ will first uncover the ports 12^a, 12^b, which will allow the gases of the combustion within the cylinders to assume a pressure quite equal

to the atmospheric pressure and then it will uncover the ports 10^a, 10^b, 11^a, and 11^b. Through these latter will pass first the fresh air contained within the canals 8^a, 8^b, 9^a, 9^b, 5 one part of the air of chamber 24 and the air within chamber 21 next to the canals.

The scavenging of the gases of combustion has thus been accomplished. Finally the rest of the contents of chambers 21 and 10 24 a mixture of combustible and fresh air will be delivered into the cylinders until equilibrium of pressure has been established between the interior of these cylinders and the pumps. A mixture of this mixture and 15 of fresh air will be formed for a new charge. Thus the first portion of the incoming gases of the cylinders, a portion of which is lost with the escaping gases of the combustion, will be composed almost solely of air and 20 the quantity of combustible taken along by the first gases will be very small. Any contact between the gases of combustion or the burning mixture and the fresh mixture is avoided, as is also the possibility of return 25 flames into the crank-pit and carbureter.

As it results from the description in the above and from the Figs. 1 to 4, this working form will have the effect that the gases introduced into the cylinders 1, 2, will be 30 first a certain quantity of pure air and then a quantity of gas composed of air and of combustible mixture simply by the constructive arrangement of the two pumps without using any special distributing member. The 35 sought-for result has therefore been obtained at little expense.

The motor may turn in both directions likewise. The regulating of the motor is effected by means of devices mounted within 40 in the passages 13^a, 13^b. If the load is small the cylinder 2 may be cut out by means of the checking member 17 in order to save fuel.

The two chambers of the crank-pit 2 may 45 be provided with means for recollecting the lubricant spattered by the rods and cranks of the shafts, thus avoiding its being taken along with the combustible mixture and the fresh air and passing into the combustion 50 chambers of the cylinders 1, 2. The port-holes 10^b and 11^b may have a smaller axial length than the ports 10^a and 10^b as is indicated by dotted lines for the port 11^b in Fig. 3 and arranged so as to have the pistons 55 uncover these ports later than the ports 10^a and 11^a. In the case of direct communications 25, 26 between the canals 8^a and 8^b, 9^a and 9^b are omitted, communications may be substituted therefor leading from the inside 60 of the cylinders at the moment when the ports 10^a and 10^b, 11^a and 11^b are both uncovered. The scavenging will also occur, but less effectually than before. Moreover the useful stroke of the pistons 6, 6¹ is di-

minished as the ports 10^b and 11^b will be 65 earlier uncovered by the said pistons.

According to Fig. 5 the communication between the canals 8^a and 8^b, 9^a and 9^b takes place owing to a hollow 29 provided within the pistons 6 or 6¹ and corresponding at the 70 given moment either with the ports 10^a and 10^b, or with the ports 11^a and 11^b.

If the axial length of the ports is diminished in this case, in order to reduce as much as possible the reduction of the useful 75 stroke also their total area will be reduced which is not of any benefit.

The motor may have more than one pair of motor cylinders opposite to each other and be combined with more than one pump 80 for the combustible mixture and also with more than one air pump for scavenging purposes.

The partition wall between the two chambers of the crank pit may also be a stationary wall provided with a bearing for the 85 crank-shaft.

Claims:

1. In an internal combustion engine, comprising a cylinder, a piston in the cylinder, 90 a closed crank pit, there being an explosion chamber at the outer side of the piston, an intake chamber at the inner side of the piston, and gas and air chambers in the closed crank pit, a crank shaft, a crank extending 95 through a wall separating the intake chamber from the chambers in the crank pit, and means whereby air and gas are drawn into said chambers by the operation of the piston, there being intake and exhaust ports 100 in the cylinder and passages from the gas chamber to the inlet ports with communications between the passages and the air chamber in the crank pit so that when the intake and exhaust ports are open, air is first admitted to the cylinder to scavenge the same before the fresh gas is admitted thereto.

2. In an internal combustion engine, comprising a plurality of cylinders in pairs, with each pair of cylinders in alinement, a 110 piston in each cylinder, a closed crank pit between the cylinders, there being air and gas chambers provided in the closed crank pit, and means whereby gas is drawn into the gas chamber and air into the air chamber by the operation of the said pistons, 115 there being intake and exhaust ports in said cylinders, and passages from the gas chamber to the inlet ports in the cylinders with connections between said passages and the air chamber in the closed crank pit, so that when the intake and exhaust ports are open, air is first admitted to the cylinders to scavenge the same before the fresh gas is admitted thereto.

3. In an internal combustion engine, comprising a plurality of cylinders in pairs, with each pair of cylinders in alinement, a 120

piston in each cylinder, there being an explosion chamber at the outer side of the piston, and an intake chamber at the inner side of the piston, a closed crank pit between each pair of cylinders and having separated gas and air chambers therein, a crank shaft, cranks extending between the crank shaft and the respective pistons, and means whereby in the operation of one piston, gas 10 is drawn into the intake chamber associated therewith and delivered to the gas chamber in the crank pit, and in the operation of the complementary piston, air is drawn into the intake chamber associated therewith and 15 delivered to the air chamber in the crank pit, there being intake and exhaust ports in said cylinders and passages from the gas chamber in the crank pit to the intake ports with communications between the same and 20 the air chamber in the crank pit so that when the intake and exhaust ports are open, air is first admitted to the cylinders to scavenge the same before fresh gas is admitted thereto.

25 4. In an internal combustion engine, comprising a plurality of cylinders, a piston in each cylinder, there being an explosion chamber at the outer side of the piston, and an intake chamber at the inner side of the 30 piston, a closed crank pit having separated gas and air chambers therein, the capacity of the air chamber and passages leading therefrom being greater than that of the said gas chamber, a crank shaft, cranks extending between the crank shaft and the respective pistons, and means whereby in the operation of one piston gas is drawn into the intake chamber associated therewith and delivered to the air chamber in the crank pit, there being intake and exhaust ports in said cylinders, and passages from the gas chamber in the 35 crank pit to the intake ports with communications between the same and the air chamber in the crank pit so that when the intake and exhaust ports are open, air is first admitted to the cylinders to scavenge the same before fresh gas is admitted thereto, and means for controlling the admission of the 40 air and gas to the said cylinders and the admission of air and gas to the said intake chambers.

45

ber in the crank pit to the intake ports with communications between the same and the air chamber in the crank pit so that when the intake and exhaust ports are open, air is first admitted to the cylinders to scavenge the same before fresh gas is admitted thereto. 50

5. In an internal combustion engine, comprising a plurality of cylinders, a piston in each cylinder, there being an explosion 55 chamber at the outer side of the piston, and an intake chamber at the inner side of the piston, a closed crank pit having separated gas and air chambers therein, the capacity of the air chamber and passages leading 60 therefrom being greater than that of the said gas chamber, a crank shaft, cranks extending between the crank shaft and the respective pistons, means whereby in the operation of one piston gas is drawn into the 65 intake chamber associated therewith and delivered to the gas chamber in the crank pit, and in the operation of the complementary piston, air is drawn into the intake chamber associated therewith and delivered to 70 the air chamber in the crank pit, there being intake and exhaust ports in said cylinders, and passages from the gas chamber in the crank pit to the intake ports with communications between the same and the air chamber in the crank pit so that when the intake and exhaust ports are open, air is first admitted to the cylinders to scavenge the same before fresh gas is admitted thereto, and means for controlling the admission of the 75 air and gas to the said cylinders and the admission of air and gas to the said intake chambers. 80

In testimony whereof I affix my signature in presence of two witnesses.

ALBERT ISLIKER.
